UNITED STATES PATENT OFFICE.

WALTER T. KRAUSCH, OF LA GRANGE, ILLINOIS.

COAL UNLOADING, BREAKING, AND LOADING APPARATUS.

No. 814,710.

Specification of Letters Patent.

Patented March 13, 1906.

Application filed September 18, 1905. Serial No. 278,897.

To all whom it may concern:

Be it known that I, WALTER T. KRAUSCH, a citizen of the United States, residing in La Grange, in the county of Cook and State of Illinois, have invented a new and useful Improvement in Coal Unloading, Breaking, and Loading Apparatus, of which the following is a specification.

My invention relates to railway coaling stations or apparatus for unloading coal from cars, breaking it, and loading it into engine-tenders or other cars.

The object of my invention is to provide a railway coaling station or apparatus of a simple, efficient, strong, and durable construction capable of being constructed at a great saving in cost over those heretofore commonly in use and occupying a minimum of amount of room or ground-space for its capacity and by means of which coal may be unloaded from cars, broken when necessary, and reloaded into tenders or other cars very rapidly and cheaply.

My invention consists in the means I have devised and employ to accomplish this object or result—that is to say, it consists in the novel construction of parts and devices and in the novel combinations of parts and devices herein shown and described, and more particularly specified in the claims.

In the accompanying drawings, forming a part of this specification, Figure 1 is an end elevation of a coal unloading, breaking, and loading apparatus embodying my invention. Figs. 2 and 3 are vertical sections, Fig. 2 being taken on the broken line 2 2 of Fig. 3 and Fig. 3 on the broken line 3 3 of Fig. 2. Fig. 4 is a horizontal section on line 4 4 of Fig. 2. Fig. 5 is a detail vertical section on line 5 5 of Fig. 4. Fig. 6 is a detail horizontal section on line 6 6 of Fig. 5. Fig. 7 is a detail elevation of the automatic-dumping bucket. Fig. 8 is a detail diagrammatic view showing the cables and pulleys for operating the elevator-buckets.

In the drawings, A represents the main frame of the apparatus. B is a double-inclined unloading-hopper sloping both ways from its apex b, which is centrally under the unloading-car track-rails C on suitable supports C', projecting above the unloading-hopper. At the outer-lower end or edge of each of the inclines b' of the unloading-hopper B is an elevator-bucket well or pit D, extending below the lower edge of the hopper, so that the coal may discharge directly from

the inclines of the hopper into elevator-buckets on each side of the hopper. The double-incline unloading-hopper also has end inclines b² sloping from each end down onto the inclines b' to direct the coal onto said inclines b'. The unloading-hopper also has reverse back inclines b³ at its outer sides.

F F are vertically-sliding doors, one on each side of the double-incline unloading-hopper B, working in suitable guides f f on the frame and operated by lines or cables f' traveling on pulleys f² and connected to operating-lever f³ to open and close the hopper at intervals, as required.

G G are coal-breaker bars extending horizontally on each of the car-unloading tracks and over the double-incline hopper B and upon which the coal from cars X on the unloading-track C is directly discharged by dumping or shoveling and by which the operator with suitable sledges may break the pieces of coal which are too large to pass through the series of breaker-bars G down onto the hopper B.

E E are the car-loading tracks, one on each side of the main frame structure A of the apparatus.

H H are automatically-dumping elevator-buckets fitting and entering the bucket pits or wells D D and each furnished with a bail H', pivotally connected thereto by pins or pivots h below and slightly to one side of the center of gravity of the bucket. The bails H' of each of the buckets are furnished with guide-blocks h', preferably of wood, rigidly secured thereto, and which work up and down in suitable guides H², preferably formed each of a pair of angle-irons. Each of the buckets H travels up and down between suitable guides or uprights H³ H⁴, preferably of wood and furnished with metal strips or rails h². The front face h³ of each of the buckets H is made higher or deeper than the rear face thereof, so that the front of the bucket, whether loaded or unloaded, will always be the heavier side thereof. The bucket guides or uprights H³ H⁴ at the front side of the bucket are furnished with rounded or curved upper ends h⁴ to facilitate the tilting or dumping of the bucket when raised to the required position.

Each of the buckets H is furnished with rollers h⁵ to bear against the front guide-rails h². Each of the buckets H is also furnished with stop-pins h⁶ to engage the bucket-bail H', and thus limit the tilting movement of

the bucket when it rights itself, and also with stop pins or shoulders h' to engage the bucket-bail guides H' H'' and limit the tilting movement of the bucket in case it should be raised 5 too high, so that the front upper edge of the bucket might otherwise fall inside the front guides or uprights H' for the bucket. As each of the buckets H is hung by its bail, which travels in upright guides, and as the 10 pivot of the bail is set below and to one side of the center of gravity of the bucket, the bucket is self-dumping, as well as self-righting, and the front side or face of the bucket in its up-and-down movement is thus also caused 15 to lie the front bucket guides or uprights H' H'' and the front face of the bucket pit or well D , so that the coal will discharge from the incline of the unloading-hopper into the bucket without wasting or spilling or filling up the 20 pit with coal, and thus interfering with the proper operation of the apparatus.

K K are the cables for operating the buckets from the winding-drums M, the bucket-cables passing over or around suitable pulleys k k' k'' k''' k''' .

N is a double-incline loading-hopper arranged above the unloading-hopper B and having each of its inclines n provided with hinged extensions n' for delivering the coal 30 directly into tenders or cars X' on the loading-tracks E E. The hinged extension n' of the loading-hopper inclines n are furnished with counterbalance-weights n'' , connected thereto by lines n^3 passing over pulleys n^4 . 35 The loading-hopper N is furnished with sliding doors N' , operated by lines n^5 , passing over pulleys n^6 . The coal is delivered from the automatic-dumping buckets H into the loading-hopper N by chutes P P, arranged 40 above the loading-hopper.

Where the cars to be unloaded are center-dump cars, the breaker-bars from the apex of the double-incline unloading-hopper are preferably omitted, and the breaker-bars at each 45 side are located lower down, as indicated by the dotted lines in Fig. 3. The longer breaker-bars are preferably connected together at their middle portions in groups by tie-rods g and thimbles g' .

50 I claim—

1. A railway coaling-station apparatus for unloading, breaking and loading coal, comprising a car-unloading track, a double-incline unloading-hopper below said track, sliding doors for opening and closing the unloading-hopper, elevator-bucket pits at the lower 55 ends of the unloading-hopper inclines, coal-breaker bars above the unloading-hopper, a double-incline loading-hopper above the unloading-hopper, sliding doors for opening and closing the same, a pair of automatic-dumping elevator-buckets having bails hinged thereto below and to one side of the center of gravity, and provided with guide-blocks, up- 60 right guides for the guide-blocks on the 65

bucket-bails, upright guides for the buckets, stop-pins on the buckets to engage the bucket-bails and limit the righting tilting movement of the buckets, stops on the buckets engaging the bucket-bail guides to limit the dumping 70 tilting movement of the buckets, inclined chutes into which the coal is dumped from the buckets and by which it is delivered into the loading-hopper, and a winding-drum and cables and pulleys for operating the buckets, 75 substantially as specified.

2. A railway coaling-station apparatus for unloading, breaking and loading coal, comprising a car-unloading track, a double-incline unloading-hopper below said track, 80 sliding doors for opening and closing the unloading-hopper, elevator-bucket pits at the lower ends of the unloading-hopper inclines, coal-breaker bars above the unloading-hopper, a double-incline loading-hopper above the 85 unloading-hopper sliding doors for opening and closing the same, a pair of automatic-dumping elevator-buckets having bails hinged thereto below and to one side of the center of gravity, and provided with guide-blocks, upright guides for the guide-blocks on the bucket-bails, upright guides for the buckets, stop-pins on the buckets to engage the bucket-bails and limit the righting tilting movement of the buckets, stops on the buckets 90 engaging the bucket-bail guides to limit the dumping tilting movement of the buckets, inclined chutes into which the coal is dumped from the buckets and by which it is delivered into the loading-hopper, and a 95 winding-drum and cables and pulleys for operating the buckets, the inclines of said loading-hopper having hinged extensions and means for raising and lowering said hinged extensions, substantially as specified. 100

3. In a railway station apparatus for unloading, loading and breaking coal, the combination with a double-incline unloading-hopper, of breaker-bars above the same, doors for opening and closing the unloading-hopper, elevator-bucket pits, elevator-buckets, upright guides for the elevator-buckets, bucket-bails pivotally connected thereto below and to one side of the center of gravity, upright guides for the bucket-bails, guide devices on the bucket-bails engaging said upright guides, a winding-drum, cables and pulleys for operating the elevator-buckets and stops on the elevator-buckets engaging the bucket-bail guides to limit the dumping tilting movement of the buckets, substantially as specified. 115

4. In a railway station apparatus for unloading, loading and breaking coal, the combination with a double-incline unloading-hopper, of breaker-bars above the same, doors for opening and closing the unloading-hopper, elevator-bucket pits, elevator-buckets, upright guides for the elevator-buckets, bucket-bails pivotally connected thereto be- 120 125 130

low and to one side of the center of gravity, upright guides for the bucket-bails, guide devices on the bucket-bails engaging said upright guides, a winding - drum, cables and pulleys for operating the elevator-buckets and stops on the elevator-buckets engaging the bucket-bail guides to limit the dumping tilting movement of the buckets, and stops on the buckets engaging the bucket-bails for limiting the righting tilting movement of the buckets, substantially as specified.

5. In a coal unloading, breaking and loading apparatus, the combination with an unloading-hopper, of breaker-bars above the unloading-hopper, a bucket-pit at the lower edge of the unloading-hopper, an automatic-dumping elevator-bucket, a bail pivotally connected thereto below and to one side of the center of gravity, guides on the bucket-bail, upright guides engaging the guides on the bucket-bail and upright guides for the bucket, substantially as specified.

6. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto below and to one side of the center of gravity, guides on the bucket-bail, upright guides engaging the guides on the bucket-bail and upright guides for the bucket and stops on the bucket engaging the bucket-bail guides to limit the dumping, tilting movement of the bucket, substantially as specified.

7. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto below and to one side of the center of gravity, guides on the bucket - bail, upright guides engaging the guides on the bucket-bail, and upright guides for the bucket, and stops on the bucket engaging the bucket-bail to limit the righting tilting movement of the bucket, substantially as specified.

8. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto below and to one side of the center of gravity, guides on the bucket - bail, upright guides engaging the guides on the bucket-bail, upright guides for the bucket, stops on the bucket engaging the bucket-bail guides to limit the dumping tilting movement of the bucket, and stops on

the bucket engaging the bucket-bail to limit the righting tilting movement, of the bucket, substantially as specified.

9. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto below and to one side of the center of gravity, guides on the bucket - bail, upright guides engaging the guides on the bucket-bail and upright guides for the bucket and a loading-hopper above the unloading-hopper, substantially as specified.

10. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto below and to one side of the center of gravity, guides on the bucket - bail, upright guides engaging the guides on the bucket-bail and upright guides for the bucket and a loading-hopper above the unloading-hopper, and a chute for receiving the coal from the elevator-bucket and delivering it to the loading-hopper, substantially as specified.

11. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto below and to one side of the center of gravity, guides on the bucket - bail, upright guides engaging the guides on the bucket-bail and upright guides for the bucket, and a winding - drum, cable and pulleys for operating the elevator-bucket, substantially as specified.

12. In a coal unloading, breaking and loading apparatus, the combination with an unloading-hopper, of breaker-bars above the unloading-hopper, a bucket-pit at the lower edge of the unloading-hopper incline, an automatic-dumping elevator-bucket, a bail pivotally connected thereto and to one side of the center of gravity, guides on the bucket-bail, upright guides engaging the guides on the bucket-bail and upright guides for the bucket, a winding - drum, cable and pulleys for operating the elevator-bucket, a sliding door for the unloading-hopper, and an operating-lever line and pulleys for operating the sliding door, substantially as specified.

WALTER T. KRAUSCH.
